CONTAINER AND COOLING MEANS
THEREFORJohn L. Kellogg, Chicago, Ill., assignor to
Helen L. Kellogg, Chicago, Ill.

Application October 30, 1933, Serial No. 695,735

6 Claims. (Cl. 62—91.5)

This invention relates to an improved type of portable container particularly adapted for holding liquids such as malt beverages, milk, and the like during shipment, and the principal object of the invention is to provide a container of the type referred to, having refrigerating means embodied therein for maintaining the contents of the container in a cool condition to prevent the same from deteriorating during shipment and storage preparatory to consumption.

A further object of the invention is to provide a container of the type referred to, having a refrigerating means embodied therein, which is designed to utilize efficiently the cooling power of a concentrated refrigerant such as solidified carbon dioxide, thereby making it practicable to utilize a refrigerant of this type in lieu of ice for the cooling of beer, food products, and the like during shipment.

Other objects and advantages of the invention will be apparent from the following detailed description, taken in connection with the accompanying drawings wherein I have shown the preferred form in which I have thus far contemplated applying the principles of the invention.

Referring to the drawings:

Fig. 1 is a vertical section through a barrel-shaped container constructed in accordance with the principles of the invention;

Fig. 2 is a vertical section through the refrigerating element portion of the container, the view being taken on line 2—2 of Fig. 1;

Fig. 3 is a fragmentary plan view of the outer end of the refrigerating element;

Fig. 4 is a vertical section through a container showing a modified form of construction of the refrigerating element; and

Fig. 5 is a plan view of the lower end of the container shown in Fig. 4.

In the transportation of beer and other malt beverages, considerable expense is incurred in maintaining the kegs or barrels of beer at a sufficiently low temperature to prevent deterioration and impairment in quality of the beverage. At the present time ice is the refrigerant commonly used to cool the barrels, and the use thereof involves undue expense because of lack of satisfactory means for effectively utilizing the cooling power of the ice. Also under the present practice there is considerable danger of having the beer become over-heated during the transfer of the barrels from the shipping cars to the retailing establishments. In accordance with my invention, I embody directly in the container, or barrel, a refrigerating unit which will serve to keep the contents of the container at a uniformly low temperature both during the period of shipment as well as during the time of storage preparatory to use. The refrigerating element which I propose to use, and which is illustrated in the accompany-

ing drawings, is particularly designed for the use of solidified or liquefied carbon dioxide as the refrigerating medium, this substance being a concentrated form of refrigerant, as compared to ice, for example. However, in referring to the use of solidified carbon dioxide or the more commonly used expression, "dry ice", it should be understood that I do not necessarily confine myself to the use of this particular substance as the refrigerating medium.

Referring first to Figs. 1—3, the barrel or container comprises: an inner sheet metal receptacle consisting of a body or side wall 6, and end walls 7 and 8, the latter being either formed as an integral part of wall 6 or being welded thereto to form a liquid-tight connection; and an outer sheet metal casing consisting of a body or side wall 9 and end wall 11 and 12, the latter in the embodiment shown being formed as an integral part of wall 9 and the brim or edge portions thereof being reinforced by annular ribs or tubes 13.

As shown in Fig. 1, the outer casing wall 9 is separated from wall 6 to provide an intervening space which, as presently will appear, serves as a colling chamber for the body of liquid 14 contained in the inner receptacle, and similarly head walls 11 and 12 are arranged in spaced relation to head walls 7 and 8, respectively, the space thus provided at each end of the container forming a continuation of the space which intervenes between the body or side walls 6 and 9. The inner and outer receptacle walls are held in spaced relation by means of a pair of annular tubes 15 which are positioned approximately midway between the head ends of the container and which completely encircle the latter, thereby serving both as a reinforcing as well as a spacing means for walls 6 and 9. The container is provided with the usual filling bung ring 16 which is closed by a bung 17, and a tap bung ring 18 is provided in the upper head end of the container, said ring being closed by a tap bung 19.

In accordance with my invention, a refrigerating element, designated generally by the numeral 21, is secured in the lower head end of the container and serves to supply a gaseous refrigerant, in the present instance carbon dioxide, to the cooling chamber surrounding the body wall 6 and the head walls 7 and 8 of the inner receptacle. Referring particularly to Fig. 2, the refrigerating element 21 comprises: a head 22; a tubular member 23 which is fixedly secured at its outer end to the head 22; and a casing or housing member 24 which is likewise secured at its outer end to head 22, the members 23 and 24 being arranged in spaced relation on head 22 as shown for a purpose which will presently be explained.

The head 22, which includes as an integral part thereof the tubular members 23 and 24, is re-

movably secured in the lower head walls 8 and 12 of the container by means of a supporting ring 25 which is welded in an opening formed in the head walls 8 and 12, and which is threaded 5 interiorly as indicated at 26 to engage corresponding threads formed exteriorly on head 22. The refrigerating element consisting of head 22 and tubular members 23 and 24 is thus removably secured in the container head walls, the members 10 23 and 24 projecting directly into the body of liquid 14. The tubular member 23 is closed at its inner end by an end wall 27, thereby providing an elongated tubular compartment for holding a mass of solidified carbon dioxide, or 15 dry ice, 28. The outer end of this compartment is closed by a cork stopper 29 which extends through an opening 31 formed in head 22. A finger piece 33 is secured in the outer end of stopper 29, and a split ring 34, contained in an 20 annular groove formed in the wall of opening 31, engages the outer end of stopper 29 to releasably hold the same in closed position in the outer end of tube 23. A gasket 35 is interposed between ring 25 and a marginal flange portion 25 36 formed on head 22, thereby providing a gas-tight seal between these parts. Flange 36 is provided with a pair of diagonally disposed openings 37 which may be engaged by a wrench to effect removal of the refrigerating element.

30 It will be apparent that, in order to make economical use of the cooling power of the mass of dry ice 28, it is necessary to provide means for preventing excessive radiation and transmission of heat to the walls 6, 7, and 8 and also to provide means for preventing excessive cooling, or possibly freezing, of the liquid which contacts the outer casing wall 24 of the refrigerating element. To this end I provide a path for the circulation of vaporized refrigerant from the mass 40 28 in the element 21 through the cooling chamber or space which lies between the inner and outer receptacle walls. The inner end wall 27 of tube 23 is provided with a series of apertures 38 through which vaporized carbon dioxide may 45 pass into the space intervening between tube 23 and casing 24. The gas is conducted from this latter space through a branched vent or opening 39 formed in head 22, to an annular space 41 formed by a groove which is cut from the inner 50 wall of ring 25. A safety plug 40 is inserted in the outer end of vent 39 to provide for escape of gas in the event that the pressure becomes excessive. The gas is conducted from this annular space 41 through a series of laterally extending openings or vents 42 into the space intervening 55 between head walls 8 and 12, which space, as previously pointed out, forms part of a continuous cooling chamber which extends completely around walls 6, 7, and 8 of the inner 60 receptacle. As the gas emerges into the space between lower head walls 8 and 12, it circulates around the body or side wall 6 and finally reaches a series of vents or openings 43 formed in the upper head wall 11, through which openings the 65 gas passes into the surrounding atmosphere. The reinforcing ribs or tubes 15 are apertured as indicated at 44 to prevent obstruction of the flow of gas. Assuming the barrel to be in the position shown in Fig. 1, it will be apparent that, 70 as the gas flows from element 21 outwardly between the head walls 8 and 12 and then upwardly between body walls 6 and 9, it will become gradually warmed by reason of absorption of heat from the walls 6, and also by reason of the inward 75 radiation of heat from outer wall 9. By properly

gauging the quantity of refrigerant employed, I have found that, in refrigerating beer for example, the temperature of the gas leaving vents 43 may be quite accurately held within the desired range of from 40° to 50° F.

5 In order to retard evaporation and flow of gaseous carbon dioxide from element 21, I provide in the space intervening between walls 6 and 9 a body of loose wool packing 45, and similarly I provide between walls 8 and 12, and 7 10 11 a layer of loose wool packing 46. The purpose of this packing is to check the rate of evaporation and flow of gas from element 21 around the walls of the inner receptacle to the outlet vents 43. If this space were not filled 15 with some suitable insulating packing such as loose wool, pulverized cork, or the like, the flow of gas would be unduly rapid, and the refrigerant would become quickly expended. This insulating mass also retards conduction and radiation of 20 heat from the surrounding atmosphere through walls 6 and 9 to the interior of the container.

A body of loose wool 47 is likewise placed in the space intervening between tubular member 23 and casing member 24 of the refrigerating element. The purpose of this mass of insulating material is twofold. It serves to retard evaporation 25 of carbon dioxide from the mass 28, and the rate of flow thereof through ports 39 and 42 to the cooling chamber, thereby conserving the cooling 30 power of the refrigerant. It also serves directly as an insulating body to prevent excessive cooling, and possible freezing of the liquid immediately surrounding casing 24. The temperature 35 of the solidified carbon dioxide is -109° F. Beer or milk and other liquids contained in the receptacle would thus be quickly frozen, if means were not provided for insulating the mass 28 from the body of fluid.

By reason of the fact that the refrigerating 40 element 21 is removably secured in ring 25, it is possible to substitute therefor other elements of various lengths and having greater or less capacity for storage of dry ice. The element 21 in effect constitutes a cooling cartridge which may 45 be of any desired length, the cartridge being replaceable so that greater cooling capacity may be provided, as for example where the containers are intended for shipment to great distances, or are intended to be kept in storage for comparatively 50 long periods of time. Although in the embodiment shown the members 23 and 24 of the element 21 are cylindrical in form, it will be apparent that they may be made in any shape which may be best suited to the particular type of container 55 employed.

In the embodiment of the invention shown in Figs. 4 and 5, the general construction of the container is quite similar to the form shown in Figs. 1-3. The inner receptacle consists of a body wall 60 48 and end walls 49 and 51, and the housing or casing which is spaced therefrom consists of a body wall 52 and end walls 53 and 54, the wall 53 being provided with vents 55 which allow escape 65 of carbon dioxide gas in the manner described in connection with Figs. 1-3. In this embodiment, however, the refrigerant container comprises a flat pan-shaped vessel 56, the side walls 57 of which project at right angles to the bottom wall to engage over a sleeve portion 58, the latter constituting an integral part of the lower head wall 54. As shown in Fig. 4, the sleeve or flanged portion 58 merely consists of the downwardly turned 70 edge portion of the walls of an opening formed in wall 54.

5 A mass of solidified carbon dioxide 59 is contained in the vessel 56 and gradually evaporates therefrom to provide a stream of cooling vapor which passes through the cooling chamber to the outlet vents 55. A body of loose wool packing 61 is placed between walls 48 and 52, and similarly strips of loose wool packing 62 are placed between the spaced head walls of the container, the purpose of this packing, as previously explained, being to retard evaporation and the rate of flow of refrigerant, and also to prevent radiation and conduction of heat to the interior of the container.

10 The vessel 56 removably engages over the sleeve portion 58 and is held in position by a removable head wall 63 which is locked in position by a split ring 64, the latter engaging within a groove 65 formed in the outer head wall 54, as clearly shown in Fig. 5. A body of loose wool packing 66 is interposed between walls 63 and 54 and serves to insulate vessel 56.

15 This form of construction of the refrigerating unit likewise permits of replacement of the mass of refrigerant 59 after the same has become expended, this being accomplished by merely removing split ring 64, head wall 63, and the body of insulating material 66, whereupon the vessel 56 may be removed and refilled. While in this form the refrigerating element does not extend into the body of liquid within the container, it nevertheless provides for effective cooling by reason of the comparatively large area which lies adjacent the lower head wall 51 and also, of course, by reason of the circulation of the gas 20 through the cooling chamber surrounding walls 48, 49, and 51.

25 The foregoing detailed description has been given for clearness of understanding only, and no unnecessary limitations should be understood therefrom, but the appended claims should be construed as broadly as permissible in view of the prior art.

30 What I regard as new and desire to secure by Letters Patent is:

35 1. A portable refrigerating container comprising a receptacle having an inner wall and an outer wall spaced therefrom to provide a cooling chamber for the circulation of refrigerant, and a refrigerating element secured in a wall of the container, said element including a supporting head, and a double walled body supported on said head and having a storage compartment therein adapted to contain a mass of solidified gaseous refrigerant, said head and the inner wall 40 of said body having openings therein to provide for circulation of gaseous refrigerant from the storage compartment through the space between the walls of said body and thence into the cooling chamber.

45 2. A portable refrigerating container comprising a receptacle having an inner wall and an outer wall spaced therefrom to provide a cooling chamber for the circulation of refrigerant, and a refrigerating element secured in a wall of the container, said element including a supporting head, a double walled body supported on said head and having a storage compartment therein adapted to contain a mass of solidified gaseous refrigerant, said head and the inner wall of said body having openings therein to provide for circulation of gaseous refrigerant from the storage compartment through the space between the walls of said body and thence into the cooling chamber, and closure means arranged to permit 50

75 refilling of the refrigerant compartment without

necessitating removal of the element from the container.

3. A portable refrigerating container comprising a receptacle having an inner wall and an outer wall spaced therefrom to provide a cooling chamber for the circulation of refrigerant, and a refrigerating element secured in a wall of the container, said element including a double walled compartment extending into the interior of the receptacle and adapted to contain a mass of 55 solidified gaseous refrigerant, the walls of said compartment having openings therein to permit flow of gaseous refrigerant into the cooling chamber, and closure means arranged to permit refilling of the refrigerant compartment without necessitating removal of the element from the container.

4. A container of the character set forth comprising a receptacle having a double wall, the outer wall being spaced from the inner wall to provide a cooling chamber for the circulation of refrigerant, a refrigerating element secured in a wall of the container, said element including a supporting head, an elongated hollow body supported on said head and adapted to contain a mass 20 of refrigerating substance, an outer shell carried on the head in spaced relation to said body and enclosing the latter, said head being apertured to provide communication between the cooling chamber and the space around said body, and a 25 mass of porous insulating material interposed in the space between said elongated body and shell for retarding volatilization of refrigerant and the rate of flow thereof into said cooling chamber.

30 5. A container of the character set forth comprising a receptacle having a double wall, the outer wall being spaced from the inner wall to provide a cooling chamber; a refrigerating element secured in a wall of the container, said element including a supporting head, an elongated hollow body mounted on said head and adapted to contain a mass of refrigerating substance, an outer shell carried on the head in spaced relation to said body and enclosing the latter, said head 35 being apertured to afford communication between the cooling chamber and the space around said body, and a mass of porous insulating material interposed in the space between said elongated body and shell for retarding volatilization of refrigerant and the rate of flow thereof into the cooling chamber; and a second mass of porous insulating material disposed in said cooling chamber for further retarding flow of refrigerant 40 around the inner wall of the container.

55 6. A portable refrigerating container for malt beverages and the like comprising a barrel-shaped receptacle having an inner wall and an outer casing spaced therefrom to provide a cooling chamber around the body and head portions of the receptacle, a head wall portion of said casing having an opening formed therein, the edge portions of said opening being flanged outwardly to provide a sleeve, a refrigerant-containing vessel comprising a relatively flat pan having side walls adapted to releasably engage said sleeve, a removable cover plate positioned in the head end of the container adjacent said vessel, and a mass of porous insulating material interposed in said cooling chamber and the space surrounding said vessel to retard volatilization of refrigerant and the rate of flow thereof from said vessel through said cooling chamber.

70 JOHN L. KELLOGG.
